UNITED STATES PATENT OFFICE

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA

CAR ROOF

Application filed May 22, 1930. Serial No. 454,799.

My invention relates to flexible car roofs wherein metal roof sheets are loosely secured to the car and to each other by seam covers that permit relative movement of the sheets to a limited extent so as to be able to accommodate themselves to the distortions of the car body.

The principal object of the present invention is to provide means for preventing water and light from entering the car through the eaves ends of the roof seams. Other objects are simplicity, cheapness of construction and compactness of design.

The invention consists in the eaves flashing and in the construction, combinations and arrangements of parts hereinafter described and claimed.

In the accompanying drawings, which form part of this specification and wherein like symbols refer to like parts wherever they occur,

Fig. 1 is a plan view of a portion of a car roof embodying my invention, portions being shown broken away to more clearly illustrate the invention,

Fig. 2 is an enlarged transverse section through the eaves portion of the roof on the line 2—2 of Fig. 1,

Fig. 3 is a vertical cross-section through one of the roof seams at the side plate,

Fig. 4 is a perspective view of one of the flashing members,

Fig. 5 is a vertical transverse section through the eaves portion of the car provided with a wooden side plate and a modified form of eaves flashing,

Fig. 6 is a vertical cross-section on the line 6—6 of Fig. 5; and

Fig. 7 is a perspective view of the modified form of eaves flashing.

My invention is applicable to metal roofs for cars having either wood or metal frame members of any suitable construction. Referring to Figs. 1 to 4, inclusive, my invention is shown in connection with a roof substructure comprising metal Z-bar side plates 1 that are connected by metal carlines 2 of substantially inverted channel-shaped section with outwardly projecting base flanges 3 at the bottoms of their side walls. The Z-bar side

plates 1 are arranged with their webs horizontally and with one flange 4 in and extending upwardly. As shown in the drawings, each end of a carline 2 is rigidly secured to an adjacent side plate 1 by means of an angle-shaped carline bracket 5, the two flanges of which are riveted one to the undersides of the base flange 3 of said carline and the other to the inner face of the upstanding inner flange 4 of said side plate.

Metal roof sheets 6 slope downwardly from eaves to ridge of the car between carlines and are supported between the side plates on purlines 7 that extend longitudinally of the car beneath the carlines and are bolted to the base flanges 3 thereof. At the eaves of the car, the roof sheets 6 are removably supported on metal side fascia members 8 of substantially T-shaped cross-section that extend longitudinally of the side plates 70 with their stems rigidly secured flatwise to the upstanding inner flange 4 thereof and with their flanges disposed uppermost and supporting the eaves ends of the roof sheets. The sheet supporting flanges of the T-shaped 75 side fascia members slope crosswise of said members at an angle corresponding to the slope of the roof sheets.

The roof sheets are provided at their eaves ends with depending flanges 9 that overhang 80 and are spaced from the outer edges of the top flanges of the side fascia members. The roof sheets are provided with upwardly offset side marginal portions 10 that are inclined upwardly and terminate in upstanding side marginal flanges 11 that extend substantially from end to end of the sheets and are spaced away from the adjacent side walls of the carlines.

Weatherproofing members in the form of inverted channel-shaped seam covers 12 straddle the carlines and the upstanding side marginal seam flanges 11 of adjacent roof sheets, the side walls of said seam covers and said seam flanges being normally spaced 95 apart throughout their length. The tops of the seam covers bear flatwise against the tops of the carlines and are riveted or otherwise rigidly secured thereto adjacent to the ridge and eaves. The seam covers 12 are 100

provided along the lower edges of their side walls with outstanding base flanges 13 that conform to the slope of the upwardly offset side marginal portions 10 of the roof sheets 5 and are arranged to rest or bear flatwise on said portions, thereby holding the roof sheets down on the car. The eaves end portions of the seam covers are provided with depending eaves flanges 14 which overhang and are 10 spaced from the end portions of the depending eaves flanges 9 of adjacent sheets.

In order to prevent water and light from entering the car at the eaves ends of the 15 seams and carlines and thus damaging the lading, metal eaves flashing members A are mounted on the car substructure adjacent the eaves ends of the seams. As shown in Fig. 4, each of these eaves flashings comprises a rectangular base portion 15 provided at its 20 outer or eaves end with a depending flange 16, which is bent inwardly at its lower end, and along its side margins with upstanding flanges 17. The base portion 15 of the eaves 25 flashing A is also provided intermediate its upstanding side marginal flanges 17 with an upstanding hood portion 18 which extends from the inner end of said base portion to the depending flange 16 at the outer end thereof. The top of the hood portion 18 30 slopes downwardly from the inner end thereto to a point adjacent to the outer end thereof where it is curved downwardly and merges into the plane of said base portion where it is turned down to form the depending 35 end flange 16, thus closing the outer end of said hood portion. The inner margin of the base portion 15 of the eaves flashing is provided with upstanding flanges 19 that are 40 of the same depth as the side flanges 17 and extend from said side flanges to the sides of the hood portion 18.

The flashing member A is positioned on the car substructure with its hood portion 18 straddling the end portion of a carline 2, 45 with its base portion 15 resting on the sheet supporting flange of the side fascia member 8 and extending inwardly above the base flanges 3 of said carline and beneath the upwardly offset side marginal portions 10 of 50 adjacent roof sheets, and with its depending eaves flanges 16 hooked beneath the outer edge of said sheet supporting flange.

By the arrangement described, any water 55 that climbs over the eaves end portions of the side seam flanges of the roof sheets drains into the pan-shaped base portions of the eaves flashings and is discharged over the side of the car. The eaves flashings also 60 serve as shields to cut down the amount of light which may enter the car through the eaves end of the seams. In the modified form of flashing shown in Figs. 5 to 7, inclusive, the entry of light in the car is further prevented by the extensions or wings 23 of the 65 main hood flashing, which bear against the

opposite sides of the carline and the inner face of the side plate.

In Figs. 5 to 7, inclusive, a modified form of eaves flashing is shown which is adapted for a car having a wooden side plate 1a, side 70 sheathing boards 20 secured to the outer face of said side plate, and a side fascia board 8a extending longitudinally of the car at the upper ends of said side sheathing boards. In the construction of the car, the eaves ends 75 of the roof sheets are supported on the tops of the side plate, side sheathing boards, and side fascia board, and the ends of the carlines 2a are seated in notches 21 in the tops of the side plates and have depending end flanges 22 that are bolted to the outer side faces of the side plates. The arrangement of roof sheets and seam covers is the same as that shown in Figs. 1 to 3, inclusive. The modified eaves flashing shown in Figs. 5 to 7, inclusive, comprises a hood flashing A1 which is substantially the same as the hood flashing shown in Fig. 4, except that the depending flange 16a at the outer end of the modified flashing is not bent inwardly, as shown in 80 Fig. 4. Secured to each of the flanged inner corner portions of the base portion of the hood flashing A1 is a rectangular tab or wing flashing or extension 23, which extends beyond the adjacent inner end and side of 85 said base portion. Each wing flashing 23 is provided along the edge thereof with an upstanding flange 24 which extends longitudinally of the hood portion of the main flashing A1, a portion of which bears against the inner face of the side wall of said hood portion; and the outside margin of said wing 90 flashing that extends beneath the corner of the main flashing is provided with a depending flange 25.

The modified eaves flashing is positioned on the car with its hood portion covering the end of the carline, with its base portion resting on the tops of the side plate, sheathing and fascia, and extending beneath the raised side margins of adjacent roof sheets, and with its depending flange 16a nailed to the outer face of the side fascia board 8a. The extensions or wings 23 at the inner end of the hood flashing A1 are disposed on opposite 100 sides of the carline 2a with the upstanding flanges 24 at their adjacent ends bearing against the side walls of said carline. The depending outside marginal flanges 25 of the extensions 23 bear flatwise against the inner 105 face of the wood side plate 1a and are secured thereto preferably by nails.

Obviously, the hereinbefore described construction admits of considerable modification without departing from the invention. 110 Therefore, I do not wish to be limited to the precise arrangements shown and described.

What I claim is:

1. A car roof having a substructure including carlines, roof sheets arranged between 115

carlines and supported at their eaves ends on said substructure, said sheets being provided along their side margins with upstanding flanges, seam covers straddling the carlines and adjacent roof sheet flanges, and an eaves flashing supported on said substructure adjacent to the eaves corners of adjacent sheets, said eaves flashing comprising a hood portion adapted to straddle the end of a carline and a base portion resting on said substructure and extending on opposite sides of the carline beneath the eaves corners of adjacent sheets.

2. A car roof having a substructure including carlines, roof sheets arranged between carlines and supported at their eaves ends on said substructures, said sheets being provided along their side margins with upstanding flanges, seam covers straddling the carlines and adjacent roof sheet flanges, and an eaves flashing supported on said substructure adjacent the eaves corners of adjacent sheets, said eaves flashing having a hood portion adapted to straddle the end of the carline and a base portion resting on said substructure and extending on opposite sides of the carline beneath the eaves corners of adjacent sheets, and wing members secured to the inner corners of said flashing member, said members being provided with flanges adapted to bear against the side walls of the carline and depending flanges adapted to be secured to the substructure.

3. A car roof having a substructure including carlines, roof sheets arranged between carlines and supported at their eaves ends on said substructure, said sheets being provided along their side margins with upstanding seam flanges, seam covers straddling the carlines and adjacent roof sheet flanges, and an eaves flashing supported on said substructure adjacent the eaves corners of adjacent sheets, said eaves flashing having a hood portion adapted to straddle the end of the carline and a base portion resting on said substructure and extending on opposite sides of the carline beneath the eaves corners of adjacent sheets, said base portion being provided with upstanding flanges along its inner and end margins.

4. A car roof having a substructure including carlines, roof sheets arranged between carlines and supported at their eaves ends on said substructure, said sheets being provided with upwardly offset side marginal portions that terminate in upstanding side marginal flanges, seam covers straddling the carlines and adjacent roof sheet flanges, and an eaves flashing supported on said substructure adjacent the eaves corners of adjacent sheets, said eaves flashing having a hood portion adapted to cover the end of the carline and a base portion resting on said substructure and extending on opposite sides of the carline beneath raised side marginal portions of adjacent sheets, said base portion being provided along its inner and end margins with upstanding flanges, and along its outer margin with a depending flange

adapted to overhang the eaves edge of the substructure.

5. A car roof having a substructure including carlines, roof sheets arranged between carlines and supported at their eaves ends on said substructure, said sheets being provided along their side margins with upstanding flanges, seam covers straddling the carlines and roof sheet flanges, and an eaves flashing supported on a substructure adjacent the eaves corners of adjacent sheets, said eaves flashing having a hood portion adapted to straddle the end of the carline and a base portion resting on said substructure and extending on opposite sides of the carline beneath the eaves corners of adjacent sheets, and wing members secured to the inner corners of said flashing member, said members being provided with flanges adapted to bear against the side walls of the carline and depending flanges adapted to be secured to the substructure.

6. A car roof comprising side plates, carlines connecting said side plates, side fascia members secured to said side plates, roof sheets arranged between carlines and supported at their eaves ends on said side fascia members, said sheets being provided along their side margins with upstanding flanges, seam covers straddling the carlines and roof sheet flanges, and eaves flashings supported on said side fascia members adjacent to the eaves corners of adjacent sheets, each of said eaves flashings having a hood portion adapted to straddle the end of a carline and a base portion resting on the fascia member extending on opposite sides of said carlines beneath the eaves corners of adjacent sheets.

7. A car roof comprising side plates, carlines connecting said side plates, side fascia members secured to said side plates, roof sheets arranged between carlines and supported at their eaves ends on said side plates, said sheets being provided along their side margins with upstanding flanges, seam covers straddling the carlines and adjacent roof sheet flanges, and eaves flashings supported on said side plates adjacent to the eaves corners of adjacent sheets, each of said eaves flashings having a hood portion adapted to straddle the end of a carline and a base portion resting on the side plate and extending on opposite sides of said carline beneath the eaves corners of adjacent sheets, and wing members secured to the inner corners of said flashing member, said wing members being provided with flanges that bear against the side walls of said carline and depending flanges that are secured to the inner face of the side plate.

8. A metal eaves flashing comprising a base portion provided with flanged ends and an upstanding hood portion intermediate said ends, said base portion being also pro-

vided along its outer edge with a depending flange.

9. A metal eaves flashing comprising a base portion provided with flanged end margins and an upstanding hood portion intermediate said flanged end margins, said base portion being also provided along its outer edge with a depending flange and along its inner edge with upstanding flanges that extend from the end marginal flanges to the hood portion.

10. A metal eaves flashing comprising a base portion provided with flanged end margins and an upstanding hood portion intermediate said flanged end margins, said base portion being also provided along its outer edge with a depending flange and along its inner edge with upstanding flanges that extend from the end marginal flanges to the hood portion, and wing members secured to the inner corners of the base portion of said flashing, said extensions having flanged edges disposed parallel to and bearing against the side walls of the hood portion of said flashing and depending flanges disposed parallel to the depending flange at the outer edge of said flashing.

Signed at New Kensington, Pennsylvania,
